UNITED STATES PATENT OFFICE.

THOMAS THOMPSON, OF NEW LONDON, WISCONSIN.

TRACE-HOLDER.

No. 858,922.

Specification of Letters Patent.

Patented July 2, 1907.

Application filed January 20, 1906. Serial No. 296,976.

To all whom it may concern:

Be it known that I, THOMAS THOMPSON, a citizen of the United States, and a resident of New London, in the county of Waupaca and State of Wisconsin, have invented a new and Improved Trace-Holder, of which the following is a full, clear, and exact description.

My invention relates to holders for the traces of harness, its principal objects being to provide a simple, convenient and durable device for both the retaining 10 of trace upon the swingletree and for holding the loose end of said trace.

Reference is to be had to the accompanying drawings forming a part of this specification, in which similar characters of reference indicate corresponding parts 15 in all the figures.

Figure 1 is a perspective view of one embodiment of my invention. Fig. 2 is a bottom plan view thereof. Fig. 3 is a longitudinal section on the line 3—3 of Fig. 1, and Fig. 4 is a transverse section on the line 4—4 of 20 Fig. 3.

I have indicated at 10 the end of a swingletree, the outer extremity of which is adapted to enter a slot 11 in a trace 12, said trace often having beyond the point of engagement with the swingletree a free end 13 of considerable length.

At some distance from the end of the swingletree, and extending transversely of its lower side, is a pivot member 14 of my improved holder, which is preferably formed of spring wire. This is here shown as rotatably mounted by means of a hinge-plate 15 surrounding it and being secured to the swingletree. At one extremity of this pivotal portion the holder extends along the swingletree for a short distance at 16, then is bent substantially at right angles at 17 and is 30 curved over the opposite or upper side, terminating near the center at 18. From this point a longitudinal portion 19 reaches adjacent to the trace where it is bent to furnish a loop 20 passing over said trace. Through the swingletree is an opening 21 to receive an arm 22 depending from the loop. This arm has at its lower extremity a latch portion or enlargement 23 adapted to engage a metallic bar or contact member 24 fixed to the underside of the swingletree and furnishing a surface more resistive of wear than the wood of which the swingletree is formed. The portion of the holder at this side of the pivot member is so bent that when the arm 22 is within the opening 21 it will bear against the wall of said opening, thus preventing rattling. The portion of the holder at the opposite side of the pivot from that 40 which has just been described rises at 25 in a direction substantially at right angles to the longitudinal por-

tion 19, and has at its upper end above the swingletree a retaining projection 26 extending back in a direction generally parallel to the pivot member.

The latch 23 being sprung out of engagement with 55 the contact member 24, the holder may be turned by virtue of its pivotal support, thus withdrawing the arm from the swingletree opening. This allows the application of the trace to the swingletree, it slipping over it until it reaches a point at the inner side of the opening. The holder may now be swung down until it is latched, the trace being now securely held against accidental displacement. The portions 25 and 26 furnish, with the swingletree, an opening through which the loose end of the trace may be passed, thus maintaining 60 it in contact with the swingletree and preventing its hanging over the thill and contacting with the wheel. When so placed, this portion of the trace does not interfere with the disengagement of the holder from the swingletree opening since the arc through 65 which the projection 26 moves is so flat that it approaches parallelism with the upper edge of the trace. My improved holder entirely obviates the difficulties arising from the use of the comparatively limp, leather tongue commonly employed, which is difficult to insert, 70 and the spring which in this connection is liable to break. Moreover its mounting is such that no strains are brought upon its elements, the movement of release and engagement being directly toward and from the portion of the swingletree which it engages, and being wholly provided for by its pivoting.

Having thus described my invention I claim as new and desire to secure by Letters Patent:

1. The combination with a swingletree, of a trace-holder pivoted upon one side of the swingletree and curved around 85 and upon the opposite side, into and out of engagement with which it may move.

2. The combination with a swingletree, of a trace-holder extending transversely of the swingletree and being pivoted thereto and then curved around and extending longitudinally upon the opposite side of said swingletree and co-operating therewith.

3. The combination with a swingletree, of a trace-holder extending transversely of the swingletree and being pivoted thereto and then curved around and extending longitudinally 95 upon the opposite side of said swingletree and having at its outer extremity a looped portion.

4. The combination with a swingletree, of a trace-holder extending transversely of the swingletree and being pivoted thereto and having one end extending longitudinally of the swingletree and its other end substantially at right 100 angles thereto.

5. The combination with a swingletree having an opening in its end, of a trace holder having a transversely extending member pivoted to the under side of the swingletree, one end of the pivoted member being curved up over

and upon the upper side of the swingletree and extending lengthwise thereof and provided with a loop at its end, the other end of said member being bent at right angles to the swingletree forming therewith a keeper for the end of the trace.

6. The combination with a swingletree having an opening in its end, of a trace holder pivoted to the swingletree intermediate of its ends, one end of the holder being bent to extend longitudinally of the swingletree and to engage

with its terminal the opening in the swingletree, and its other end bent to extend transversely of the swingletree and terminating in an inwardly extending projection.

In testimony whereof I have signed my name to this specification in the presence of two subscribing witnesses.

THOMAS THOMPSON.
